UNITED STATES PATENT OFFICE.

WILLIAM A. JENNINGS, OF RAYTOWN, MISSOURI.

CYLINDER-BORING MECHANISM.

Application filed April 14, 1922. Serial No. 552,739.

To all whom it may concern:

Be it known that I, WILLIAM A. JENNINGS, a citizen of the United States, and resident of Raytown, Jackson County, 5 Missouri, have invented a certain new and useful Improvement in Cylinder-Boring Mechanism, of which the following is a complete specification.

This invention relates to apparatus for 10 the boring or reborning of cylinders, and more especially of internal combustion engines, and has for one of its objects to produce an internal bearing for the cutter head so that such cutter head may always be 15 held in alinement and against any wobbling or springing which develops into a more or less eccentric motion and leads to an untrue boring of the cylinder.

Another object is to produce a device of 20 this character which has an adjustable mandrel so that the device may be adapted to be used with cylinders of varying lengths.

A further object is to produce a cutter head provided with an internal bearing so 25 constructed as to be readily adjustable to compensate for wear.

A still further object is to produce a device of the character described of simple, 30 strong, durable, efficient and inexpensive construction; and in order that it may be fully understood reference is to be had to the accompanying drawing, in which:

Figure 1 is a side elevation of a portion 35 of a drill press and illustrates in section an engine block with the device of the invention in operative relation thereto;

Figure 2 is a section on the line II—II of Figure 1;

Figure 3 is an enlarged section on the 40 line III—III of Figure 1;

Figure 4 is an enlarged section on the 45 line IV—IV of Figure 1;

Figure 5 is a section taken on the line 50 V—V of Figure 3;

Figure 6 is a central vertical section 55 through a modified form of the invention; and

Figure 7 is a section on the line VII—VII of Figure 6.

50 In the said drawing, where like reference characters identify corresponding parts in all of the figures, 1 represents the standard of a drill press, 2 the base thereof and 3 the end of the customary driving shaft.

55 Mounted upon the base in any suitable

manner and preferably of sufficient length to accommodate an engine block, is a bridge member 4, formed with an opening 5 of greater diameter than the largest cylinder to be bored and axially alined with the driving shaft 3, and also formed with a pair of inverted T-slots 6 for a purpose which will hereinafter appear.

Bolted as at 7, or otherwise secured to the underside of the bridge piece and closing the opening 5, is a retaining member 8 in which is driven, shrunk or otherwise rigidly secured, the lower extremity of a vertical shaft 9, which will be positioned as near as possible with its axis in vertical alinement with the axis of the driving shaft 3.

An engine block 10 is now disposed with one of its cylinders receiving the stub shaft 9, and such cylinder is axially alined with said stub shaft and the heads of a series of long bolts 11 may now be engaged in the T-grooves 6 of the bridge piece, and at their upper ends said bolts pass through perforations in the ends of a pair of cross 80 bars 12 and by means of the customary nuts on the bolts, it will be evident that clamping pressure may be exerted on the cross bars to rigidly retain the engine block against side slip on the bridge piece, as 85 will be readily understood. The method of securing the block, however, is unimportant provided it is held rigidly in place. As illustrated, the engine block is positioned with its crankcase inverted, although it will be apparent that it could 90 be positioned with its crankcase resting on the bridge piece if found desirable.

The mandrel comprises a pair of tubular members 13 and 14, the former telescoping 95 into the latter, and each of them is provided with a series of registering perforations 15, through any pair of which a key 16 may be passed for securing the parts in any desired position of longitudinal adjustment, 100 depending upon the type of press and the work to be done. The upper end of the member 13 is formed with a tapered extremity 17 for engagement within the customary socket formed in the lower end of the operating shaft 3 of the drill press.

The lower end of the mandrel member 14 is threaded as at 18 for threaded engagement with the internally threaded upper end of a cutter head 19, it being understood 110

in this connection that the internal diameter of the member 14 is greater than the diameter of the stub shaft 9.

Substantially centrally of its length the cutter head is split horizontally as at 20 for substantially one-half of its diameter, and the lower portion thus formed is provided with a pair of ears 21 and with a central bore or bearing 22, preferably, initially of 10 slightly less diameter than that of the stub shaft 9. The split bearing thus formed, possesses more or less resiliency and the ears 21 will normally be spaced a slight distance apart. One of the ears 21 is formed 15 with a pair of threaded openings and engaged in one of said openings and bearing at its end against the other ear 21 is a screw 24 formed with a socketed head. Upon rotation of the screw in the proper direction, 20 it will be evident that upon the application of sufficient force, the pair of ears 21 will be forced further apart and the diameter of the bearing 22 will be correspondingly increased. Engaging the second threaded 25 opening in the ear, is the threaded extremity of a bolt 25 passing through a perforation in the other ear and formed at its end with a head for engagement by a wrench or the like. The internal bore 22 of the 30 cutter head is adapted to find a bearing on the shaft 9 and as said bore gradually increases in diameter under wear, the screw 24 will be retracted, and the ears 21 will move toward each other due to the 35 resiliency of the split ring and the diameter of the bore will be correspondingly decreased. When the entire contractive force of the split ring has been exhausted, the bolt 25 may be rotated to draw the ears together and further decrease the diameter of 40 the bore 22, as will be readily apparent. It will be evident from the above that the life of the bearing 22 is thus doubled, as it is first expanded, allowed to contract, and 45 then forcibly contracted.

Running horizontally of the cutter head and at the opposite side thereof from the ears 21 is a slot 26 for the reception of a bit 27, the rear end of the bit being slightly 50 recessed for abutment with a socketed adjusting screw 28 threaded in the rear end of the slot, it being evident that the adjustment of this screw may be used to vary the depth of the cut made by the bit. Between 55 the rear end of the bit and the cutting end thereof, a second socketed screw 29 engages the cutter head and presses against the side of the bit in such a manner as to force said bit toward the axis of the cutter head, and 60 a third socketed screw 30 threaded in an enlargement 31 of the cutter head engages the opposite side of the bit from the screw 29 and at a slight angle, and tends to counteract the pressure of the screws 28 and 29. It 65 will be apparent from the above that the

bit will be rigidly held in position against movement or springing action in any direction within its socket 26, and that it may be adjusted to vary the cut as found desirable.

The stub shaft 9 is of such proportion as 70 to inhibit springing movement, and as the cutter head has a bearing on said stub shaft it will be evident that it will accurately maintain a fixed center and that the pressure on the stub shaft will always fall in 75 the radius of the shaft passing through the point of contact of the bit with the cylinder wall. It has been found that a split ring is unnecessary for the operation of the cutter head, because the thrust from the 80 point of the bit is radially inward and hence applied against the rigid shaft at all times. The split ring construction, forming a complete bearing, is desirable to overcome any possible tendency the bit might have to 85 jump or dig into the cylinder walls, but it can be dispensed with as above stated.

It will be apparent from the above that the stub shaft is depended upon to center the bit, and that even if the axis of such stub 90 shaft is slightly out of line with the driving shaft 3, the stub shaft will counter-act any tendency the cutter head may have to wobble, and that, therefore, this wobbling or eccentric motion must occur in the mandrel 95 and drive shaft, between the lowermost bearing of the latter and the cutter head.

It is desirable to point out in this connection that the bridge piece 4 is cut away as at 100 5, to permit the cutter head and bit to enter therein, thus boring the entire length of the cylinder without inversion of the engine block or the elevation or lifting of the latter. When the engine block is positioned with its crankcase down, it will be evident that the opening 5 is unnecessary, as the cutter head will exit into the crankcase enlargement as will be readily understood.

In the device as illustrated in Figures 6 and 7, a modified form is shown, in which: 9 illustrates the stub shaft, 14 the lower mandrel member, and 10 a cylinder which is desired to bore with tapering walls.

In order to accomplish this result, the stub shaft 9 must itself be tapered or, as illustrated, a tapering cone 32 may be slipped in position on said stub shaft, it being evident that it is immaterial whether the cone revolves around the shaft or not, as will be readily understood. It will be apparent that in this instance it is impossible to employ a cutter head forming a complete ring, as described in connection with Figures 1 to 5, inclusive, as in such case, the cutter head could not slide down the tapering cone. A cutter head 33 having threaded engagement with the mandrel and of substantially semi-circular form is, therefore, employed (see Figure 7), it being evident that a cutter head of this character will be free for down-

ward travel on the cone. It is desirable to point out in this connection that the mandrel for use in producing a tapering or irregular boring, must be flexible or provided with a 5 universal joint 34, (see Figure 1) in order to permit of downward travel of the cutter head and away from center, as otherwise the cutter head and cone will bind, involving too great an expenditure of power to overcome 10 the friction which would thus be produced. A bit 34 is carried by the cutter head 33 in a similar manner to that above-described in connection with the cutter head 19, and in such a position that the cutting point will lie 15 in a radius of the shaft 9 passing substantially through the center of the circumference of the cutter head. It will be apparent that by varying the shape of the stub shaft or equipping it with an irregular sleeve 32 20 that the cutter could be caused to operate in conformity with the stub shaft or irregular sleeve, and produce a correspondingly irregular boring in the cylinder.

From the above description it will be apparent 25 that I have produced a device of the character described, which possesses all of the features of advantage set forth as desirable, and while I have described and claimed the preferred embodiment of the 30 same, I reserve the right to make all changes

properly falling within the spirit and scope of the appended claims.

I claim:

1. A cylinder boring machine comprising a drive shaft capable of lateral movement, a 35 rigidly secured vertical stub shaft alined with the drive shaft, and adapted to project into a cylinder to be bored, said stub shaft having a tapered portion, a cutter head carrying mandrel attached to the drive shaft 40 and telescoping the stub shaft, said cutter head bearing on the stub shaft on the cutter side of the head only whereby the tapered stub shaft serves as a guide for the cutter head in its movement through the cylinder. 45

2. A cylinder boring machine comprising a drive shaft having therein a universal joint, a rigidly secured vertical stub shaft alined with the drive shaft, and adapted to project into a cylinder to be bored, said stub 50 shaft having a tapered portion, a cutter head carrying mandrel attached to the drive shaft and telescoping the stub shaft, said cutter head bearing on the stub shaft on the cutter side of the head only whereby the tapered 55 stub shaft serves as a guide for the cutter head in its movement through the cylinder.

In witness whereof I hereunto affix my signature.

WILLIAM A. JENNINGS.
